Benjamin Lapham of Waterford New York.

Letter's Patent

The Schedule referred to in this Letter Patent and making part of the same containing a description in the words of the said Benjamin Lapham himself of his improvement in the forcing pump.

To all persons to whom these presents shall come— Benjamin Lapham of Waterford in the County of Saratoga and State of New York and Creator— Know ye that I the said Benjamin Lapham have invented, contrived, made and put to use a new and useful improvement— to wit, an improved forcing pump calculated to lessen, or nearly dispense with the friction occasioned by the pistons in the common pumps now in use; and also to prevent entirely or very nearly the loss of water escaping between the piston and the sides of the pump, which improved pump by varying its size and some other slight variations applies with equal fitness to all the purposes of raising water from the common house pump for domestic use, to the fire engines or forcing pump for extinguishing fire. The chief component parts of this pump like all other pumps, are, the body or chamber which receives and discharges the water, and the piston.

The body or chamber of this Pump may be of Block tin, of Pewter, or of cast iron or any other suitable metal or mixture of metals, and is cast or formed in two halves, each half being nearly in the form of the common basin. Each half has a flange round the edge, through which the two halves are secured together by screw bolts, so that when the two are secured together, the whole is somewhat in form of a nut. But the opposite edges of this chamber have each a cylindrical projection, each projection extending in length a little beyond the edge of the flange, and on the end of each projection is a circular flange, one half of each projection and flange being attached

1816

to, and making part of the half of the chamber to which it is respectively
belongs - The piston consists of a circular piece of strong and sublim-
inal leather inserted between the two flanges, which extending through
divides the said body, or chamber into two equal halves - To the outer
end of this piece of leather is attached by proper flanges, nut & screw
the end of the piston rod, which piston rod passes from said leather
at right angles, and through the sides of the chamber, which has a
projection in the centre in which it is made tight with proper
stuffing, so that the said piston rod, can act and seal without
suffering the water to escape, said piston or circular piece of leather
is supported on each side by two triangular pieces, of sheet iron, brass
or any other suitable metal, which pieces are so placed and of such
size and such angles, that while the base of each piece rests against
a shoulder on the inside of its respective basin, each of the other
two sides describes a radius from the insertion of the piston in the
centre to the said shoulder of base, and each should, making a chord
of about sixty degrees, or any aliquot number, into which the arcs
of the inside of the basin can be divided; the said plates of metal
cover the leather on each side, except that the jaws are so far
open, as to suffer the leather to bend a sufficient distance between
the plates, the jaws on the opposite sides being exactly opposite
each other. Thus, a double chamber is formed by the piston, one
half being on each side of it, a kind of dome with a flange
round its base is fastened by screws through the flanges to the ends
of the above mentioned cylindrical projections, and each dome ter-
minated in a cylindrical neck to which the receiving and discharging
tubes of the pump are coupled by connecting screws. On each of these
domes are two valves, one on each side of the piston or division of
the two chambers, those on the receiving side opening inward, and those
on the discharging side opening outward. When the piston or partition of
leather above described is moved alternately towards each side by the
piston rod, the respective chambers are thereby alternately enlarged and

contracted, and by means of the valves, each chamber fills from below up, it expands and discharges above, as it contracts. As the attitudes or positions in which this pump may be placed, and the modes in which the lever or handle may be applied, are so various, it is unnecessary to specify any one in particular. The plates of metal are secured in each side of the leather, by rivets passing through both plates and through the leather. When the above is constructed on a larger scale for extinguishing fire, the chamber will be best made of cast iron, or of sheet copper, but to whatever purpose applied, I hereby claim the double chamber and leather partition piston, supported by plates of metal, as above specified, as essential parts of this my invention. I, witness that the above is a true specification. I have hereunto set my hand and seal in Waterford aforesaid on the seventeenth day of June in the one thousand eight hundred and thirty three.
